N. WHITE,
KEY STOP,
APPLICATION FILED OCT. 23, 1923.

Patented Nov. 28, 1922.

Fig. 1.

UNITED STATES PATENT OFFICE.

NELSON WHITE, OF DES MOINES, IOWA, ASSIGNOR TO MONROE CALCULATING MACHINE COMPANY, OF NEW YORK, N. Y., A CORPORATION OF NEW YORK.

KEY STOP.

Application filed October 23, 1920. Serial No. 419,027.

To all whom it may concern:

Be it known that I, NELSON WHITE, a citizen of the United States, resident of Des Moines, in the county of Polk, and State of Iowa, have made a certain new and useful Invention in Key Stops; and I declare the following to be a full, clear, and exact description of the same, such as will enable others skilled in the art to which it appertains to make and use the invention, reference being had to the accompanying drawings and to letters or figures of reference marked thereon which form a part of this specification.

Figure 1 is a cross-section through the keyboard of a calculating machine made in accordance with the invention.

Figure 2 is a detail sectional view of the lower portion of a key stem and parts mounted thereon.

Figure 3 is a detail perspective view of a cross piece.

Figure 4 is a detail perspective view of a washer.

The invention has relation to stops for depressible operating keys, such for instance as the keys of calculating machines or registers, and it consists in the novel construction and combinations of parts, as herein-after set forth.

In the accompanying drawings illustrating an embodiment of the invention, the numeral 1 designates the depressible keys of a calculating machine such for instance as disclosed in the patent to Monroe No. 1,306,606, dated June 10, 1919, said keys being shown in said patent as having stems 2 of planular or flat form and provided with lower cam heads 4', acting in the depression of the keys to move pivotally rock bar members 3, related to each denominational series of keys, and coming to rest upon said rock bar members to limit the downward movement of the key.

Each key has a retracting spring 4, bearing at one end against the framing or frame plate 5, and at the other end bearing against a stop member of cross piece 8 to be described, a washer 6 of the key stem being interposed between said spring and said cross piece.

The key stem is provided with a longitu-

dinal slot 7, and fitting neatly in this slot is the cross piece 8, of planular or flat form, having a height about equal to the height of said slot, extending laterally at each side of the key stem, and provided with an upper notch 8' of a breadth about equal to the thickness of the key stem, whereby when the cross piece is inserted within the notch of the key stem and raised upwardly, the end walls of said notch will engage the sides of the key stem and the inner wall of said notch will engage the upper wall of the slot of said stem, said cross piece being thereby fixed in position against upward or edge-wise movement, and the engagement of the cross piece with said slot serving as a guide in assembling the parts and also tending to fix the cross piece in position against lateral movement.

The washer 6 is provided with a central parallel wall slot 9 which the key stem neatly engages, and with a second parallel wall slot 10, at right angles to and intersecting the first named slot and engaging the cross piece 8, whereby the latter is held rigidly in position upon the key stem. The upper wall of washer 6 has engagement with upper shoulders 11 of said cross piece, thereby limiting the upward movement of the washer under the influence of the spring 4. The spring 4 will hold the parts in proper assembled position, it being necessary to disengage the notch 8' from the key stem and to disengage the washer from the cross piece before the latter can be displaced.

In assembling the parts, a lower washer 12 and cushion 13, being first engaged with the key stem, the latter is inserted into engagement with a parallel wall slot 14 of the frame plate from below (neatly engaging said slot); the coiled spring 4 is engaged with the key stem from above and slid downwardly thereon to said frame plate; the washer 6 is engaged with the key stem from above and also slid downwardly thereon, said washer being pressed downwardly below the slot 7 of the key stem said spring being thereby compressed and put under tension; after which the cross piece 8 is inserted within the slot 7 of the key stem and raised upwardly to engage its notch with the key stem as stated, the washer being then per-

mitted to rise under the influence of the spring to engage the cross piece as stated.

The advantages attained are that the key is limited in its downward movement by engagement of the lower end of the cross piece with the frame plate, thereby relieving the rock bar member 3 aforesaid of strain, and permitting the same to be made lighter in construction. Furthermore the assembly is facilitated, since all the parts are freely engageable and do not have to be driven to place. The cross pin of the said patent is liable to drop out unless it is driven tightly in engagement with its perforation in the key stem which is difficult on account of the many adjacent parts, the operator being cramped for room; whereas the cross piece 8 being inserted in position as stated will be held securely in place.

20 It is obvious that the invention is equally applicable to key stems of round or other form in cross section, and that the washers 6 may be omitted if desired and the springs 4 act directly upon the cross pieces 8.

25 I claim:

1. In a stop device for the purpose described, a stationary member provided with an aperture, a stem slidably engaging said aperture, a coiled spring surrounding said stem and bearing at one end against said member, and a device engaging said stem and adapted in the movement of said stem in one direction to compress said spring and to contact with said member to limit the movement of the stem.

2. In a stop device for the purpose described, a stationary member provided with an aperture, a key stem slidably engaging said aperture and having a slot, a coiled spring surrounding said stem and bearing at one end against said member, and a device engaging said slot and adapted in the movement of said stem in one direction to compress said spring and to contact with said member to limit the movement of the stem.

3. In a stop device for the purpose described, a stationary member provided with an aperture, a key stem slidably engaging said aperture and having a slot, a coiled spring surrounding said stem and bearing at one end against said member, and a device engaging said slot and adapted in the movement of said stem in one direction to compress said spring and to contact with said member to limit the movement of the stem, said device having a notch engaging a portion of the key stem marginal to said slot and being so held by said spring.

4. In a device for the purpose described, 60 a stationary member provided with an aperture, a key stem slidably engaging said aperture and having a slot, a coiled spring surrounding said stem and bearing at one end against said member, a device engaging said slot and adapted in the movement of said

stem in one direction to compress said spring and to contact with said member to limit the movement of the stem, and means adapted to maintain said device in engagement with said slot.

5. In a stop device for the purpose described, a stationary member provided with an aperture, a key stem slidably engaging said aperture and having a slot, a coiled spring surrounding said stem and bearing at 75 one end against said member, a device engaging said slot and adapted in the movement of said stem in one direction to compress said spring and to contact with said member to limit the movement of the stem, and a washer interposed between said device and said spring and adapted to maintain said device in said slot.

6. In a stop device for the purpose described, a stationary member provided with an aperture, a key stem slidably engaging said aperture and having a slot, a coiled spring surrounding said stem and bearing at 80 one end against said member, a cross piece 85 engaging said slot and having a head adapted in the movement of said stem in one direction to compress said spring, said cross piece being adapted to contact with said member to limit said movement, and a washer interposed between the head of the 95 cross piece and said spring and having intersecting slots engaged by said stem and said cross piece.

7. In a stop device for the purpose described, a frame provided with an aperture, 100 a key stem engaging said aperture and having a lower head, a coiled spring fitting over the key stem and resting on said frame, a washer fitting over the key stem and forming a bearing for the upper end of said 105 spring, and means engaging the key stem adapted to fix said washer in position against the tension of said spring and to contact with said frame to limit the downward movement of said key.

8. In a stop device for the purpose described, a frame provided with an aperture, a key stem engaging said aperture and having a longitudinal slot and a lower head, a 110 coiled spring fitting over the key stem and resting on said frame, a washer fitting over the key stem and forming a bearing for the upper end of said spring, and a cross piece 115 engaging said slot and having an upper notch engaging the key stem portion marginal to said slot and adapted to fix said washer in position against the tension of said spring and to contact with said frame to limit the downward movement of said key.

9. In a stop device for the purpose described, a frame provided with an aperture, a key stem engaging said aperture and having a lower head, a coiled spring fitting over the key stem and resting on said frame, a 130

washer provided with intersecting slots and forming a bearing for the upper end of said spring, and a member engaging the key stem and adapted to fix said washer in position 5 against the tension of said spring and to contact with said frame to limit the downward movement of the key, the respective intersecting slots of said washer engaging respectively the key stem and said member, to hold the latter in position. ¹⁰

In testimony whereof I affix my signature in presence of two witnesses.

NELSON WHITE.
